B. R. TUNISON

PROCESS OF EXTRACTING OILS, FATS, ETC

Filed April 12, 1920

Burwell R. Tunison, Inventor
By his Attorney
Prindle, Wright & Prindle

UNITED STATES PATENT OFFICE.

BURNELL R. TUNISON, OF NEW YORK, N. Y., ASSIGNOR TO U. S. INDUSTRIAL ALCOHOL CO., A CORPORATION OF WEST VIRGINIA.

PROCESS OF EXTRACTING OILS, FATS, ETC.

Application filed April 12, 1920. Serial No. 373,309.

To all whom it may concern:

Be it known that I, BURNELL R. TUNISON, a citizen of the United States, residing at New York, in the county of New York and State of New York, have invented a certain new and useful Improvement in Processes of Extracting Oils, Fats, Etc., of which the following is a specification.

My invention relates particularly to a process of extracting oils, fats, and similar materials, and is applicable to the recovery of oily, fatty, and waxy materials from many different materials.

The object of my invention is to provide a process by means of which the substances, above referred to, may be recovered from many different materials in an advantageous manner and without the marked disadvantages which have previously accompanied extraction processes. Hitherto, various extraction processes have been used, but many difficulties have developed therein arising from the production of emulsions with the water present, and from the necessity of using solvents which are volatile, as well as combustible, and therefore dangerous, and which are often very expensive. The object of my invention is to avoid these disadvantages by using as a solvent one or more esters, alcohols, ethers, and ketones alone or mixed together, which are of such a character that the solvent will readily mingle with the solid materials from which the aforesaid substances are to be extracted, notwithstanding the presence of a large percentage of water therein, without the formation of emulsions therewith, said solvent having a boiling point higher than the boiling point of many of the solvents previously used, and not being of a very inflammable character. The object is to use a solvent which can thereafter also be readily separated from the other substances taken up by it from the materials subjected to the extraction process. Furthermore, by the use of a solvent having a somewhat higher boiling point than in the case of many of the solvents formerly used, there is a much smaller loss of the solvent due to leakages in the apparatus, and the danger of combustion is consequently much less than would otherwise be the case. A further object is to use a solvent which will form with water a constant boiling mixture, so that the water will most effectively evaporate with the solvent, thus

providing a solvent mixture which is considerably less inflammable even than the solvent constituents which form the constant boiling mixture with the water. Still another object is to remove in this way much of the water present in the materials treated, which in other processes would be an additional source of expense owing to the necessity of extracting the same initially in the extraction process. Again a further object is to use ethyl acetate as one of the solvent constituents, notwithstanding its great avidity for water.

Further objects of my invention will appear from the detailed description thereof contained hereinafter.

While my invention is capable of embodiment in many different forms, for the purpose of illustration I shall describe only certain forms of my invention hereinafter, and while it is capable of being carried out in connection with many different types of apparatus, I have shown only one type of apparatus for use in connection therewith in the accompanying drawing, in which—

The figure is a diagrammatic cross-section of an apparatus which may be used in connection with my invention.

For example, in carrying out my invention, my process may be applied to the extraction of mineral, vegetable, animal, or essential oils, as well as fats, waxes, alkaloids, drugs, and similar materials from seeds, skins, wool, and fabrics of all kinds including woven fabrics, etc.

In the case where cotton seed meal is to be treated for the extraction of the cotton seed oil contained therein, a quantity of the meal which might contain 7 or 8% by weight of water is introduced into an extraction vessel 1 through a manhole 2 and is adapted to be removed therefrom by means of a door 3. In the bottom of the extraction vessel 1, there is a coil 4 for the injection of live steam. The extraction vessel 1 is enclosed within a solvent vessel 5, the contents of which may be heated by a steam coil 6, arranged for the application of indirect heat to the solvent mixture. The solvent mixture contained in the solvent vessel 5 is preferably comprised of 83% by weight of ethyl acetate, 8% by weight of alcohol, and 9% by weight of water, although the percentages of the constituents may vary to a considerable extent. The

contents of the solvent vessel 5 when desired may be removed through a cock 7. When the solvent mixture is vaporized by the heat from the coil 6 the vapors thereof 5 pass upwardly around the outside of the extraction vessel 1 into a tubular reflux condenser 8 provided with a current of cooling water with the aid of inlet and outlet pipes 9 and 10. The vapors of the solvent mixture are condensed in the reflux condenser, and fall from the tubes therein back into the extraction vessel 1, which is open at the top, and when the level of the solvent mixture in said extraction vessel 1 reaches a 10 point near the top thereof, a siphon 11 leading from the bottom of the vessel 1 to the vessel 5 will siphon off the quantity of the solvent mixture contained in the extraction vessel 1, and the solvent mixture will then 15 again accumulate in the vessel 1 until it is again drawn off in a similar manner, the extraction thus proceeding intermittently in accordance with the principle of the Soxhlet apparatus, until the extraction is 20 complete. In the siphon 11 there is a by-pass cock 12 to permit the continuous flow of the solvent mixture from the vessel 1 to the vessel 5 when desired. Any vapors of the solvent mixture which are not condensed 25 in the reflux condenser pass outwardly therefrom by a tube 13 into a coil 18 of a condenser 19 having a partition 20 near the bottom of the same to provide a storage receptacle 21 in which the solvent mixture 30 will accumulate, and from which storage chamber the solvent mixture may be drawn off from time to time by means of a valved outlet pipe 22 discharging through a perforated pipe 23 into the top of the extraction 35 vessel 1. It will be understood that above the partition 20, there is maintained a body of water to cool the coil 18 and passing outwardly through the body of water, leading 40 from the storage chamber 21, there is 45 a vent pipe 24 to prevent the accumulation of any undue pressure in the chamber 21. A coupling member 25 is provided as shown, in order to connect the tube 13 with the condenser coil. When the cotton seed meal 50 has been completely extracted in this manner by the intermittent flow of bodies of the solvent mixture therethrough, the application of heat through the coil 6 is discontinued, and live steam is introduced into the 55 extraction vessel 1, so as to drive off the remainder of the solvent mixture including the water present, which is then caught and retained in the storage chamber 21 for further use. In this way, the solvent mixture 60 may be used over again a number of times for the treatment of a number of quantities of the materials to be extracted. When the quantity of water taken up by the solvent mixture is greater than found desirable, 65 the solvent mixture remaining in the cham-

ber 5 may be heated by the coil 6 to drive off the constant boiling solvent mixture, and so as to collect the entire quantity of the same in the chamber 21, after which the residual, fatty, and oily materials, as well 70 as the excess water, may be drawn off by the cock 7 and separated by decantation. In treating the cotton seed meal, it will be found that emulsions will not be formed, notwithstanding the large quantity of water 75 that may be present therin, but that there will be an exceedingly rapid extraction of the cotton seed oil, owing not only to ready miscibility of the ethyl acetate, water, and oily materials, but also to the effective 80 analysis of the ethyl acetate through the cells of the seeds. Also, in this process, inasmuch as the constant boiling mixture of ethyl acetate may be used, an extraction medium 85 is utilized which may be a by-product from the utilization of ethyl acetate in other industries, as for example, the production of films and coatings in which ethyl acetate has been used as a solvent.

In the above solvent mixture the alcohol 90 may be absent or substituted by any other liquid which would not be detrimental to the solvent action of the ethyl acetate, as for example benzol. Also, instead of the ethyl acetate, I may substitute one or more 95 other solvents that may have a similar action, as for example, one or more esters other than ethyl acetate, one or more alcohols other than alcohol and one or more ethers or ketones. For example, instead of the ethyl acetate, I may use benzol, amyl alcohol, amyl acetate, iso-butyl alcohol or iso-propyl alcohol.

While I have described my invention above in detail, I wish it to be understood 100 that many changes may be made therein without departing from the spirit thereof.

I claim:

1. In a process of extracting oily material from associated material, the step which 110 consists in treating the mass with a solvent that is composed of a constant boiling mixture of ethyl acetate, alcohol, and water.

2. The process of extracting cotton seed meal with a mixture of ethyl acetate and 115 aqueous alcohol.

3. The process of extracting cotton seed meal with a constant boiling mixture of ethyl acetate, alcohol and water.

4. The process of extracting oily material 120 with a mixture comprising ethyl acetate and alcohol, distilling off from the mixture the constant boiling mixture of ethyl acetate, alcohol, and water, and re-using this distillate for further extraction of the oily 125 material.

5. The process of treating cotton seed oil comprising extracting it with a mixture containing ethyl acetate and alcohol, removing the solvent with the extracted material con- 130

tained therein, and distilling off a constant boiling mixture of ethyl acetate, alcohol and water, reusing the distillate for further extraction, and separating the oil from the 5 water remaining in the residuum from said distillation.

6. The process of extracting oily material with a ternary mixture comprising two oil solvents and water, distilling off from the 10 aforesaid mixture a constant boiling mixture of the three ingredients, and extracting the oily material with the distillate so obtained.

7. The process of extracting oily material 15 with a ternary mixture comprising a solvent ester and another solvent not detrimental to the solvent action of the ester, and water; distilling off from the mixture a constant boiling mixture of the three ingredients; 20 and re-using the distillate so obtained for further extraction of the oily material.

8. In a process of extracting oily material, the step consisting in treating it with a constant boiling mixture of water and an 25 oil solvent that is non-inflammable and has a relatively high boiling point.

9. The process of extracting cotton seed oil with a boiling mixture comprising ethyl acetate and alcohol, and distilling off a 30 constant boiling mixture of ethyl acetate, alcohol and water for reuse in the extracting process.

10. The process of treating cotton seed oil comprising extracting it with a boiling mixture 35 containing ethyl acetate and alcohol, removing the solvent with the extracted ma-

terial contained therein, distilling off a constant boiling mixture of ethyl acetate, alcohol and water, reusing this distillate for further extraction, and separating the oil 40 from the water remaining in the residuum from said distillation.

11. The process of extracting oily material with a boiling mixture comprising ethyl acetate and ethyl alcohol, and distilling off a constant boiling mixture of ethyl acetate, alcohol and water for reuse 45 in the extracting process.

12. The process of treating oily material comprising extracting it with a boiling mixture containing ethyl acetate and alcohol, removing the solvent with the extracted material contained therein, distilling off a constant boiling mixture of ethyl acetate, alcohol and water, reusing this distillate for 50 further extraction, and separating the oil 55 from the water remaining in the residuum from said distillation.

13. The process of extracting oily material with a mixture comprising an oil solvent that is non-inflammable and high boiling, and water; distilling off from said mixture a constant boiling mixture of the ingredients; and extracting the oily material 60 with the distillate so obtained.

14. The process of extracting oily material with a constant boiling mixture of ethyl acetate, alcohol, and water.

In testimony that I claim the foregoing, I have hereunto set my hand this 11th day 70 of March, 1920.

BURNELL R. TUNISON.
